UNITED STATES PATENT OFFICE.

MEYER REINGOLD, OF NEW YORK, N. Y.

GARMENT.

1,402,089.

Specification of Letters Patent. Patented Jan. 3, 1922.

Application filed May 8, 1920. Serial No. 379,911.

To all whom it may concern:

Be it known that I, MEYER REINGOLD, a citizen of Russia, residing at New York, in the county of New York and State of New York, have invented certain new and useful Improvements in Garments; and I do hereby declare the following to be a full, clear, and exact description of the invention, such as will enable others skilled in the art to which it appertains to make and use the same.

This invention relates to garments and more particularly to the class of garment known as over-alls.

The objects of the invention are to provide a garment of this type having increased utility over the garments heretofore on the market; to provide a one-piece overall; to include as a part of said overalls a hood; to adapt said hood to be also utilized as a collar when not in use as a hood; to provide for the comfort of the user and serviceability of the garment, to secure simplicity of construction and ease in donning or removing the garment, and to obtain other advantages and results as may be brought out in the following description.

Referring to the accompanying drawing, in which like numerals of reference indicate similar parts throughout the several views;

Figure 1 is a perspective view of a garment embodying my invention in use, looking at the front thereof and showing the hood thereof in lowered position forming a collar;

Figure 2 is a similar view looking at the back of the garment.

Figure 3 is a view corresponding to Fig. 1 showing the hood in raised position;

Figure 4 is a view corresponding to Fig. 2 showing the hood raised; and

Figure 5 is a fragmentary and diagrammatic view of the closure means for the garment opening.

In the specific embodiment of the invention illustrated in said drawing, the reference numeral 1 indicates the body portion of a garment constructed in accordance with my invention. This garment is what may be termed a one-piece garment in the sense that it is all together and not parts which may be separated in use, but inseparable so that the entire garment has to be put on at

one time and covers the user's person from his feet to his head, as may be seen from the drawing. The body portion 1 of the garment covers the user's torso, and is provided at its lower part with leg portions 2, and at its upper part with sleeves 3 all united as one garment.

The body portion 1 is adapted to be opened down the front from the neck thereof to the crotch as at 4, and suitable means are provided for effectually closing the garment along this line. The closure means preferred is a series of knobbed fingers 5 at one side of the opening interfitting with a similar series of knobbed finger 6 on the other side of the opening. Dilating consecutive fingers of one series will permit the intermediate fingers of the other series to become disengaged, but such dilation can only occur when begun at one end of the series and performed successively from one finger to the next. A slide is provided for doing this and for returning the fingers into interengaging position, said slide being operable by the tassel 7 attached thereto. This closure means per se is one heretofore sold upon the market and its further description or illustration is therefore deemed unnecessary. While its structure per se is old, like other closure securing means such as buttons, hooks and eyes, and so forth, its application to garments is new, and forms a feature of the present invention. Obviously by drawing the tassel 7 up or down, the garment is closed or opened accordingly with the greatest of ease and facility.

The garment is preferably of waterproof material thus adding to its utility in inclement weather, and affording the utmost protection to the user's clothes beneath at such time. It may be here noted, that this feature of the invention is enhanced both by having the garment constructed as a one-piece garment thus eliminating superfluous cracks and crevices for rain or moisture to enter, and also because of the particular closure employed which brings the opening edges closely together and effectively resists penetration of water to the inside of the garment.

An added, and perhaps the most important feature of the invention, is the provision of a hood 8, the same being constructed as

an integral part of the remainder of the garment, and being also made of waterproof material. This hood is of sufficient size and shape to be drawn up and completely cover 5 the user's head, said hood being open at its front, however, to permit the user to look out. This hood is so constructed, that when not in use as a hood it may be folded and laid back upon the body portion of the garment and form a collar therefor, (see Figs. 1 and 2). This is important, for the garment to be of value in the trade must not only be neat and attractive in appearance, but comfortable and serviceable in use. 10 15 Comfort for the user is obtained by thus constructing the hood so it will rest around the neck like an ordinary coat collar when not in use as a hood.

While perhaps other specific structures 20 may obtain the same results, I prefer to employ the one shown which consists of a neck band 9, rear cape 10 and visor portion 11 all proportioned so as to assume the requisite positions in either use as hood or collar, and 25 appropriately sewn or otherwise held together. It will be noted that the visor portion 11 extends outwardly over the eyes and forehead to form suitable protection for the same as shown in Fig. 3. The neck band 9 30 in the present disclosure is attached at its lower edge to the upper edge of the body portion 1 of the garment, and has its greatest height at the middle of the back of the garment, said neck band tapering toward its 35 ends and terminating a distance from the front opening of the garment. The rear cape 10 is attached at its lower edge to the upper edge of the neck band 9 and is adapted to be stood upright at the back of the 40 user's head with its end portions extending forwardly to the front of the garment. Said forwardly extending ends, however, preferably do not come all the way to the front opening of the garment so as to meet, but 45 are separated to afford greater freedom of movement. The visor 11 is attached to the cape portion 10 so as to extend over the user's head and downward at the side of his face, the edges of this visor converging to 50 ward a point at their lower ends. These lower pointed ends of the visor do not come all the way to the body portion of the garment, but terminate at a distance therefrom substantially equal to the depth of collar 55 which it is desired to show at the front of the garment, said pointed ends being designated by reference numerals 12.

In folding the hood to turn it back as a 60 collar, the visor 11 is first doubled outwardly over on the seam between itself and the cape 10 so the surface which is normally at the outside and over the top of the user's head lies against the surface of the cape which is normally out. When the visor is 65 thus folded, the edge thereof which as a

hood substantially encircles the user's face will pass around his neck, in substantially a horizontal plane. The visor and cape are then turned downward to overlie the user's shoulders and the line of folding will be 70 governed at the back by the height of the neck band which is such as to result in a fold suitable to give a collar effect to the hood. When the hood is desired for use as such, it is very readily unfolded and drawn 75 into place.

Obviously detail modifications and changes may be made in the manufacture of my improved garment, and I do not wish to be understood as restricting myself to the 80 exact structure shown except as may be set forth in the following claims construed in the light of the prior art.

Having thus described the invention, I 85 claim:—

1. A garment having in combination a hood, said hood having a cape portion and a visor portion joined together and adapted to be folded on the line of joining and folded back together to form a collar for the garment, said visor portion extending over the user's forehead and eyes and downward at the sides of the face, the sides of the visor portion projecting beyond the outlines of the face, and a neck band included between the body of the garment and the cape portion of the hood, the height of the neck band at the back of the garment adapted to govern the line of folding of the hood in constituting said hood a collar. 90

2. A garment having in combination a hood comprising a cape portion and a visor portion joined together, said visor portion being secured to the cape portion whereby the same will extend over the head and downward at the side of the face, the edges of said visor converging toward a point at their lower ends, said pointed ends terminating at a distance from the body of the garment. 1

3. A garment having in combination a hood comprising a cape portion and a visor portion joined together and adapted to be folded on the line of joining, said cape and visor portion being folded back together to form a collar for said garment, a neck band included between the body of the garment and the cape portion of the hood, the height of the neck band at the back of the garment adapted to govern the line of folding of the hood in constituting said hood a collar, said visor portion being attached to the cape portion so as to extend over the user's head and downward at the side of the face, the edges of said visor converging toward a point at their lower ends, the lower pointed ends of the visor terminating a distance from the body equal to the depth of the collar at the front. 1

4. A garment having in combination a 1

hood comprising a cape portion and a visor portion joined together and adapted to be folded on the line of joining and folded back together to form a collar for said garment and said visor portion being attached to the cape portion so as to extend over the user's head and downward at the side of the face, the edges of said visor converging toward a point at their lower ends, said pointed ends terminating at a distance from the body substantially equal to the depth of the collar at the front.

In testimony whereof I affix my signature.

MEYER REINGOLD.
